Term of patent 14 years

(Cl. D44—1)

Fig. 1.

Fig. 3.

Fig. 2.

To all whom it may concern:

Be it known that I, Nicholas W. Keller, a citizen of the United States, residing at New Kensington, in the county of Westmoreland and State of Pennsylvania, have invented a new, original and ornamental Design for a Cooky Cutter Carrier, of which the following is a specification, reference being had to the accompanying drawing, forming a part thereof, in which:

Fig. 1 is a side elevational view of a cooky cutter carrier, showing my new design with cutters shown in dotted lines to illustrate the manner of their association with the carrier;

Fig. 2 is a view partly in cross section on the line II-II

of Fig. 1 with the handle portions of the carrier shown in elevation; and

Fig. 3 is a cross sectional view taken on the line III-III of Fig. 2.

I claim:

The ornamental design for a cooky cutter carrier, substantially as shown and described.
